UNITED STATES PATENT OFFICE.

MANUEL BRETOS Y CLAVERIA, OF SANTYAGO, CUBA.

FOLDING DOOR.

Application filed July 13, 1923, Serial No. 651,403, and in Cuba June 6, 1923.

This invention relates to improvements in folding doors, especially to metallic folding doors, which improvements give adaptability of said doors to all kinds of iron frames in sheds or stores, said doors being usable, furthermore, in inclined or perpendicular fronts.

Another object of the invention is to provide improvements in the construction of folding doors in which the brackets of drums for folding the doors and the guide rails thereof are composed of adjustable movable parts as desirable for the installation.

Another object of the invention is to provide an improvement in the drums for rolling the doors, by means of which improvements the drums can be installed more easily, and, furthermore, there is added a clasp for connection of the top part of the door. A suitable tool is likewise provided by means of which the drums can be installed with great facility on their corresponding axles.

Another object of the invention is to provide an improvement in the hub on which the folding door drums are mounted, making the construction thereof much simpler.

Another object of the invention is to provide a secure latch for the door, and to effectively modify the means used to make the closing movement of the door smoother.

Further advantages and other considerations pertaining to the invention will be clear from the specification taken in connection with the accompanying drawings, in which the same characters of reference designate the same parts throughout, and wherein:

Figure 1 is an exterior, front elevation of a folding door constructed in accordance with the present invention;

Figure 2 is a front elevation of the interior of the door;

Figure 3 is an elevation of the top part of the door, in detail;

Figure 4 is a different elevation of said detail;

Figure 5 is a top view of the same;

Figure 6 is a horizontal section on line 6—6 of Fig. 4;

Figure 7 is a vertical section on an enlarged scale, on line 7—7 of Fig. 2;

Figure 8 is a vertical section on line 8—8 of Fig. 7;

Figure 9 is a vertical section on line 9—9 of Fig. 8;

Figure 10 is a perspective view of the hub on which a rolling drum is mounted;

Figure 11 is a perspective view of the door clasp, which is secured to each rolling drum;

Figure 12 is a side elevation of one of the rolling drums, showing the applications of a key or tool used to operate the same;

Figure 13 is an end elevation of Fig. 12;

Figure 14 is a perspective view of a key which serves as a coupling to connect the means for folding the door;

Figure 15 is a perspective view of an instrument used to operate the rolling drums.

In Figs. 1 and 2 of the drawings is represented a folding metallic door 1 having an opening 2 with a shutter 3 which has a demountable frame 4 and usual latches 5.

The means for folding the door consists of two brackets 6 and 7 that extend inwardly at the top part of the door, and one for each side of same. Referring for example, to the bracket 6 which is in every detail like the opposite bracket 7, said bracket is fixed to the top beam 8 of the door. The beam consists of a recessed section and the bracket is fixed thereto by means of an angle plate 9, which, at the top is connected by bolts 10 to the extreme front of the bracket 6. The bolts 10 pass through vertical adjusting slots 9' formed in the bracket.

The angle plate 9 is secured to the post 8 by means of bolts 11 passing through adjusting slots 9'' formed therein. The bracket 6 is further secured to the side member 12 that serves as the door guide rail, by a vertical angle plate 13 fixed to the top of the bracket 6 by means of bolts 14 passing through slots 6' in the member 13. The central part of the rail 12 is secured to the bottom of the plate 13, by means of a spaced block 15 to which the plate is fixed by means of bolts 16 and 17, the block 15 being fastened to the rail 12 by a screw 18.

The plate 13 is further secured to one of the sides 2' of the door by means of an angular clamp 19 which is fastened to the lower part of the plate 13 by means of a bolt 20 passing through a vertical slot 19' in the plate 13, and a horizontal slot 19'' in the clamp 19, and to one of the sides of the door by means of a bolt 21.

100

105

110

The plate 13 has horizontal accessory slots 13' for a purpose to be later explained.

At the lower part of each bracket 6 and 7 are provided grooves 22 for receiving the wings of the top beam 8 in case the latter is disposed in an inverted position to that shown in Fig. 4, i. e., with its wings upward.

The described assembly therefore makes the brackets 6 and 7, the plate 13 and the 10 guide rails 12 of the door adjustable by means of the connecting bolts and slots. This is furthermore effected by the grooves 13' in the plate 13 which permit placing said plate in different positions from that appearing in the drawing.

At the free ends of the brackets 6 and 7 there are horizontal grooves 23 in each of which is adjustably mounted a bolt 24 which in turn passes through a vertical groove 25 20 formed in an extension that terminates in a collar 26 which serves to support an axle 27 on which the folding drums of the door are mounted, and which axle is firmly secured by a set screw 27' screwed in the top of each 25 collar.

These collars can consequently be adjusted through the grooves 23 and 25, whereby the bolt 24 is adapted for horizontal adjustment relative to grooves 23 30 and 25. Furthermore the bolt 24 being square, cannot turn in the groove 23 as it could if it were cylindrical, when it is acted on by the force due to the tension of the drum springs.

These drums 28 and 29 are, as usual, mounted on hubs 30 of the type shown in Fig. 10.

This type of hub at its central part has an enlarged diameter provided with a notch 30' 40 for springs 31 which are lodged inside the drums 28 and 29 and a recess 30'' to lighten its weight. On either elevated side of the hub are reduced portions 30''' where the friction of the drums 28 and 29 acts. At the ends of 45 the hub are lengthwise slots 32 for receiving the lower teeth 33' of the coupling pieces or keys 33, shown in detail in Fig. 14, and which serve to fix the drum 28 to the hub 30 when the top teeth 33'' of said keys are connected in the grooves 28' of the drum.

The construction of the drums also in-

cludes three stationary pins 34, 35 and 36 with outwardly projecting ends, and in two of them is secured a clasp, as illustrated in Fig. 11, consisting of a bent rod 37 in the 55 form of a U, and with its ends 37' curved so as to fit over the projecting ends of one of the stationary pins, as pin 34, and permitting the top edge L' of the door I to engage in said clasp, as shown in Figs. 7 and 9. 60

At the same time the projections of the three stationary pins permit using a tool such as that shown in Fig. 15 and consisting of a fork having a handle 38, and prongs 39 with their ends 39' bent downwardly so as 65 to be adapted to fit over the ends of the pin on which it acts. This permits adjusting the folding drum with great ease, and without the necessity of making an entire rotation of the drum, and furthermore permits 70 finer graduation of the spring tension according to the three possible adjustment positions, all of which is clearly illustrated in Figs. 12 and 13.

It is evident that within the principles of 75 construction above enumerated, distinct changes can be made without departing from the described invention, which is claimed as follows:—

1. In combination, a pair of vertical guide 80 rails, a transverse top beam connected thereto, spacing blocks secured to the rails, a connecting plate secured to each spacing block, brackets having a slot and bolt connection with the connecting plates, support collars 85 horizontally and vertically adjustably connected to the brackets, and a drum axle carried by the collars.

2. A rolling device for a folding door, 90 comprising, an axle, a hub mounted thereon, the hub having an enlarged central portion, slots in the ends of the hub, a drum surrounding the hub and connected thereto by means of the slots, pins carried by the drum and adapted for engagement by a tool for 95 rotating the drum, and a clasp carried by one of the pins and arranged for attachment to a folding door.

In testimony whereof I have signed my name to this specification.

MANUEL BRETOS y CLAVERIA.
